UNITED STATES PATENT OFFICE.

ROBERT SPURGEON MATHIS, OF CORINTH, MISSISSIPPI.

RUG AND PROCESS FOR MAKING SAME.

Application filed March 23, 1923. Serial No. 627,243.

To all whom it may concern:

Be it known that I, ROBERT SPURGEON MATHIS, a citizen of the United States, and a resident of Corinth, in the county of Alcorn and State of Mississippi, have invented certain new and useful Improvements in Rugs and Processes for Making Same, of which the following is a specification.

This invention relates to rugs and a process for making the same.

An object of the invention is the provision of a process for forming a rug whereby the rug will be more ornamental, more serviceable and durable, and more economical to manufacture.

Another object of the invention is the provision of a process for manufacturing a rug whereby the center of the rug will have in effect a continuous flat surface whereby puckering or buckling-up of the rug will be prevented.

Another object of the invention is the provision of a rug that will have a continuous flat center and so constructed that the rug will retain its original shape and in which stretching or curling up of the edges of the said rug will be eliminated.

Other objects and advantages will become apparent during the course of the following description.

The invention is illustrated by way of example in the accompanying drawings, in which,

Figure 1 is a plan view of one form of the rug with parts outlined to show a section of the weaving.

Figure 2 is an enlarged detail view of the strand-wrapped cores sewed together and showing one stage of the process for forming the rug.

Figure 3 is a longitudinal section of one of the strand-wrapped cores.

Figure 4 is a view in perspective of a pair of the strand-wrapped cores before the strands are stitched to the cores and also before the strand-wrapped cores are stitched together.

Referring to the drawings, it will be seen that it is necessary to provide a number of strand-wrapped cores which are formed into endless bands 1 and 2 which are arranged around each other and connected together by means of stitching. In order to form an endless band, I take a flat core 3 of uniform width throughout and wrap the same with two strands of flat material 4 and 5 which I

preferably cut in uniform widths, but about half the width of the core 3. I preferably select the strands 4 and 5 of the same color but of a different color from the core 3.

The strands 4 and 5 are wrapped about the core 3 in the following manner: At the end of the core I secure an end of each of the strands 4 and 5 with the strands being extended in opposite directions from each other so that in wrapping the strands about the core, strands 5, as shown in Figure 4, will be over-laid on the upper surface of the core 3 but at an acute angle to the edge of the core so that the strand will cross said core diagonally. Strand 4 will then be brought diagonally over the same face of the core and in superposed relation with the strand 5. On the other face of the core the strand 4 is diagonally extended transversely of said face with the strand 5 being likewise extended diagonally across the face and in superposed relation with the strand 4. The wrapping is continued with the strands diagonally crossing each other until a core is completed. The result is that on one face of the core strands 5, as shown in Figure 4, will be alternately crossed by a strand 4 while on the opposite face strand 4 will be crossed by a strand 5. This alternate crossing of the strands upon opposite faces of the core will expose to view diamond-shaped sections 6 of the core thereby disclosing sections of color which are distinct from the strands 4 and 5. The strands may be of a dark color while the core may be of a more conspicuous lighter color or the strands may be of a light color while the core may have a darker shade.

One result which is obtained by the alternate crossing of the strands upon opposite faces of the core 3 is that where it is necessary to splice a strand said strand is spliced at that point where the other strand crosses it so that the splicing is covered by the overlapping or superposed strands and therefore no ragged or rough edges of the splicing is ever exposed to view and each strand then presents the appearance of a continuous strand as wrapped about the core 3.

The strand-wrapped core becomes a finished product when it is stitched by one or more rows of stitching 7, as shown in Figure 2, which binds the strands to the core.

In the construction of a rug, one or more sections of a strand-core may be stitched together by a zig-zag stitching 8 and their

ends rounded off as shown at 9 to form the center of the rug. A continuous band is formed from a strand wrapped core which is arranged around the central member 9, 5 as shown more particularly at 10, and has its inner periphery stitched to the outer periphery of the portion 9. The zig-zag stitching may be employed and may be done by hand or by machine.

10 The ends of the core are connected together as shown more particularly in Figure 4. One end of the core, as shown at 11, is cut away in V-shaped formation and the other end of the core, as shown at 12, is 15 cut in a V-shaped formation and complementary to the cut 11 so that 12 will neatly fit the cut-out portion 11. The strands are diagonally wrapped around the connected portions 11 and 12 to thoroughly cover the 20 connection and thereby present one continuous band without any breaks. Other bands are formed in a similar manner and having their opposite edges connected to the adjacent edges of alternate bands by zig-zag 25 stitching. The ends 11 and 12 of a core are secured together by stitching the strands across the joined ends of the core.

It will be seen by such a construction that the cores are non-stretchable and likewise 30 the rug cannot be pulled out of shape when in use. Furthermore, it is seen that by employing cores of a light color wrapped by strands of a dark color that these strand-wrapped cores form a certain portion of the 35 rug while other strand-wrapped cores may be employed at intervals having dark cores and strands of a lighter color thereby providing various designs with the diamond-shaped portion of the cores always exposed 40 and producing additional designs which may not be had with other forms of rugs.

The diamond-shaped sections of the core are arranged in alternate relation upon opposite faces of the core by the crossed diagonally disposed strands.

45 Both faces of a core may be of the same color or of different colors thereby adding various color schemes to the opposite faces of the rugs.

50 What I claim is:

1. A step in the process of manufacturing rugs which comprises forming a flat core, wrapping two strands of material around the core and crossing said strands diagonally upon opposite faces of the core thereby exposing portions of the core alternating between the crossed strands, and securing the crossed strands to the core by stitching.

55 2. A step in the process of manufacturing rugs which comprises forming a flat core, wrapping around the core two strands of material distinguished from the core by color and by a width approximately one-

65 half that of the said core and crossing said strands diagonally upon opposite faces of the core, thereby exposing portions of the core alternating between the crossed strands, and securing the crossed strands to the core by stitching disposed centrally and longitudinally along the core.

70 3. A step in the process of manufacturing rugs which comprises forming a flat core, wrapping two strands of material around the core, crossing one strand over the other strand in such a manner that one strand lies in superposed relation upon the other strand upon one face of the core with the last mentioned strand being crossed in superposed relation on the first strand on 75 the opposite face of the core, splicing other strands to the ends of the first mentioned strands and covering said spliced ends of the strands by a continuous overlapping portion of a crossing strand, and then 80 stitching the crossed strands and spliced ends of said strands to the core.

85 4. A step in the process of manufacturing rugs which comprises forming a flat core, wrapping around the core two strands of material and crossing said strands diagonally upon opposite faces of the core, to expose diamond-shaped portions of the core, stitching the strands to the core, forming the strand-wrapped cores into endless bands 90 of progressively increasing sizes, arranging the bands one within the other and securing the inner and outer peripheries of the bands to the adjacent contacting peripheries of 95 alternately arranged bands.

100 5. A strand adapted to be employed in the manufacture of rugs comprising a flat core, flat strands of material wrapped around the core with one strand crossing the other strand upon one face of the core and thereby disposing portions of the core alternately between the crossed strands, and stitching disposed centrally of the core for securing the overlapped portions of the strand to said core.

105 6. An annular strand adapted to be employed in the manufacture of rugs, comprising a flat core having one end sheared off at an angle and the other end having a notch complementary to the sheared off end whereby the sheared end neatly fits the notched end, stitching for locking the two ends together, flat strands of material wrapped around the core with one strand crossing the other strand upon one face of the core and thereby exposing portions of the core alternately between the crossed strands, the crossed strands covering the secured ends of the flat core and stitching disposed centrally of the core for securing 120 the overlapped portions of the strands to said core.

ROBERT SPURGEON MATHIS.
